ARTHUR H. ADAMS, OF LAKEVILLE, CONNECTICUT

TRAIN-CONTROL SYSTEM

Application filed January 5, 1928. Serial No. 610,304.

This invention relates to electric train control or signaling systems and particularly to that class of systems we may call continuous influence systems in which indications governing the progress of a train are continuously received on the train, whether moving or stationary, preferably by an inductive receiver thereon, from roadside conductors in which the original electrical indications are set up.

In accordance with the present invention codes of waves in the track distinguished by different timed intervals between the waves and preferably by two polarities (in the manner of telegraph and similar codes) are used to convey different indications to the train. By these means a practically unlimited number of indications are made available very simply.

The time marking or measuring feature of the roadside or track-current codes of my invention is further utilized in cooperation with a distance measuring means on the train to fix conditions of maximum speed. These conditions may result in mere signals or indications to the engineer or motorman that he is—or is not—exceeding a predetermined allowable speed. Or they may result—and I disclose suitable means for this—in enforcing his prompt obedience to the signals under penalty of an automatic application of the brakes. To further make the penalty effective I have arranged that such an automatic application of the brakes cannot occur without leaving a record, of which disciplinary notice may be taken. As I have shown it this record is in the form of a broken seal. Obviously many other forms of telltale or recording means well known in various arts could be applied to register the fact of an automatic brake application. By virtue of the time marking feature of the track current codes of this invention, my cab signal system is further so designed that it gives the engineer positive information on his speeds—e. g. as to whether or not he is traveling faster than is allowed in a given block. This is particularly useful in those blocks which, in the system as herein shown, are the second, behind the occupied block in which a warning

signal is given and a speed limit enforced, and which hereinafter will be briefly termed "caution" blocks.

In prior continuously inductive train control systems, the receiver has been usually adapted to respond, not to individual impulses received from a roadside conductor or from the rails, but to an alternating current or to two or more alternating currents in two or more track or roadside circuits. This has for instance been accomplished by alternating currents of different frequencies in the rails with alternating current relays, usually of a dynamometer or induction motor type, operated by the continued currents of different frequencies, but not responsive to the individual impulses of the track current. This has been also otherwise accomplished by similar relays differently responding to alternating currents of the same frequency in two different track circuits when the two currents are shifted in their relative phase. I am not aware that any system was known before this invention in which the receiver involves an instrument responsive to individual impulses or waves, or to part of an individual wave, in the roadside or track circuit.

I use preferably for the purpose a strongly polarized relay, somewhat similar to certain relays used in the telegraph art. A very sensitive and quick D. C. relay may however be used. As is well known polarized relays as a class are exceedingly sensitive, quick and reliable and can be made to operate on a very small fraction of the energy required by the usual alternating current relay. One of the main advantages, aside from the quick response to individual impulses, obtained by adopting this most sensitive form of receiving relay lies in the lower amplification required for the impulses when received on the train or intermediate amplification may be even eliminated.

In order to promote an economical and efficient system, I have conceived of the use of track currents having very abrupt changes. Half of an ordinary sine wave of commercial frequency might very well be used, or any other wave form changing at a reasonably rapid rate, without departing however

from the spirit of my invention. Nevertheless, such non-abrupt forms would require, in order to operate a quick polarized relay, a larger amplification between the inductors on the locomotive and the relay than does my preferred abruptly changed wave form. A great many suitable wave forms can be devised. I have shown in the drawings only two, illustrative of the forms having the abrupt change I prefer. One is a gradually built up current flow in the track, with as sudden an interruption as is possible. The gradual current rise will induce in the receiver on the locomotive a relatively long continued but very weak current, too weak to overcome the starting resistance—mechanical and magnetic,—of the polarized relay. On the other hand the abrupt interruption will generate a brief relatively strong impulse in the receiver. As is described formally below, Fig. 2 of the drawings shows this type of wave form. The other wave form,—see Fig. 3,—is really a mere steady direct current flow in the track, suddenly interrupted and immediately reversed. There is practically no choice between these two forms as regards their effectiveness in operating the polarized relay. Many other forms of suddenly interrupted and gradually increased current would also be equally good.

For the purposes of the particular track current controlling circuit which I illustrate the reversed steady current is assumed. This circuit, which I shall hereafter call the track circuit, is merely illustrative. Signal controlling track circuits operable with direct current in the tracks, with or without reversals, also others with alternating currents in the tracks, are so common and so well known in the art that without question many different and doubtless equally effective arrangements could be devised for this part of the system by those skilled in the railway signaling art.

In the prior art one of the great obstacles has been to measure on the train the speed or the travel of the train. Devices for this have been particularly troublesome due to the difficulty of providing a flexible shaft or a geared connection to a locomotive axle. The pounding and other conditions are such that these connections were constantly out of order. Expensive and cumbersome governors have even been devised with electrical or other connections for this purpose.

By this invention the distance traveled and the elapsed time for that travel are separately measured or marked off. This, in general, has been done in the prior art; but the use of codes of current impulses in the track or roadside conductor to mark off time, has not to my knowledge been accomplished, and offers great advantages. If it fails, it has the effect of setting up the "stop" condition.

In accordance with the present invention

the indicator of revolutions is a suitable interrupter ring with wipers mounted directly on an axle of the locomotive and giving electrical impulses in the cab over conductors therefrom.

Preferably I employ a series of relays for counting the impulses produced by said interrupter. Said relays have very slight mechanical work to do, and each is operated at a frequency very many times less than that of the main element in any of the mechanical types of counters known in the art. I have connected these relays as a set of counting relays, whereby the revolutions of the axle tend to deenergize them one by one, and so that the time-marking track code impulses tend to restore them all. I thus set up, under certain conditions, a constantly repeated race between the axle tending to count all the relays down, and the time marking impulse periodically restoring them all.

My invention however may be practised by using any well known type of mechanical or electromechanical revolution counter.

Generally stated, a system equipped with the various features of my invention, operates in the following manner:

A number of timed codes of electrical waves, preferably having very abrupt portions, are set up in the track or in other roadside conductors. The number of codes used is a matter of practical import and depends on conditions but the choice of these codes, so that no failures shall produce indications of false safety, is important. Simple means are shown, but any well known means may be used, to determine how these codes succeed each other in the blocks behind an occupied block. I have shown, besides "occupied", three conditions, "stop", "caution", and "clear". "Caution" involves a speed limit. Instead of these three conditions, my invention can equally well be practised with, besides "occupied", three or more different speed limits, as "10 miles per hour", "25 M. P. H.", "40 M. P. H.", and "unlimited". The impulses set up in the track are inductively received on the train, preferably amplified, and individually operate a receiving relay, preferably of a polarized type. Sufficiently frequent operations of this relay, by means of its local contacts, preferably maintain a locked or quiescent condition of the control apparatus. This is preferably accomplished by slow releasing relays which do not get time to release under these conditions. This is the "clear" or "full speed" or "unlimited" condition.

The control apparatus includes a recording device, being preferably a set of counting relays, to record the distance traveled since a certain instant. This device is preferably operated by an electrical interrupter on an axle of the train. A pause in the frequent operations of the receiving relay allows the

recording device to start recording the distance traveled. After the pause, operation of the same relay resets the recording device and restores briefly the mentioned quiescent condition of the control apparatus, unless during the pause, which is a feature of the code and predetermined in length a predetermined limiting distance was recorded. In this latter case the recording device has severed its own control by the polarized relay, cannot be reset thereby and so continues to record distance traveled until either the engineer applies the brakes by hand or a further position of the device is reached which applies the brakes automatically.

An alternative is the initiation of an automatic brake application by the recording device as soon as the predetermined limiting distance has been recorded, the recording device stopping at this point, and a time lag being introduced in the application of the brakes whereby the engineer can manually forestall the automatic application if vigilant. Such a time lag may be produced by many well known means.

With air-brakes their automatic applications is preferably effected through deenergizing by the recording device a solenoid which has been holding closed an air valve. If the engineer manually applies the brakes before the solenoid is deenergized the effect of the advanced position of the recording device must be neutralized, and the latter restored to the control of the receiving relay. This is preferably accomplished by resetting the recording device part way, at least far enough to restore its control to the receiving relay. The resetting is preferably done by closing an electrical resetting circuit upon a manual brake application. This resetting circuit, among other methods of operation, is very suitably closed by some form of pressure gauge making and breaking a contact and pneumatically connected to the air line of the brakes.

If the receiving relay is a balanced or unbiased polarized relay, which is preferable to the biased type, it will stay put and gives no operations on repeated impulses of the same polarity. In any case, whether in the balanced polarized relay there are received repeated impulses of one polarity or whether in either type of relay no impulses at all are received, a long continued period without any operation of the receiving relay will cause, by the means just described, an automatic application of brakes unless forestalled by a manual application. Obviously, if the train is not running, no distance will be recorded and the point of automatic application on the recording device will not be reached.

Signals, preferably visual such as lamps, may be provided to be operated,—e. g. extinguished,—at two or more positions of the re-

cording device. As the structure is shown one lamp is provided to be extinguished when the recording device is unlocked ready to start recording and another is provided to be extinguished a trifle before the recording device reaches the point of severing itself from the control of the receiving relay. The burning of both lamps indicates the locked or quiescent condition of the control apparatus which can only be due to frequent operations of the receiving relay, i. e., to a "clear" indication in the track. The extinction of the first lamp indicates the beginning of a pause code, therefore the reception of the beginning of a speed limiting or of a "stop" code. The re-lighting of the first without extinction of the second indicates that the pause code has ended—i. e. that the recording device has been reset,—before excessive distance has been recorded. Extinction of the second lamp indicates that distance has been recorded nearly sufficient to cause application of brakes automatically, unless they already or promptly are applied by hand. The steady burning, or the brief darkening or flickering of the second lamp especially, informs the engineer whether his speed is or is not within the limits prescribed. The arrangement shown is further such that the restoring of the recording device (by a brake application) to the control of the receiving relay in no way affects the visual signals which at all times faithfully relate the indications received, and the agreement of train speed therewith. As shown, the first lamp is primarily the tell-tale of the kind of code received and the second lamp primarily betrays whether or not the distance recording device moves too far in the time allowed by the pause in the code.

A large number of variations of these visual signals and of their relation to the distance recording device can be devised. For example, a series of small lamps, one extinguished by each step of the recording device, would quite graphically indicate to the engineer the proportion of his speed to the limiting speed. But the two lamps shown give all necessary indications and are preferable therefore for reasons of simplicity.

In the drawings, Fig. 1 represents a block or section of track insulated from adjacent blocks with a diagrammatic showing of a controller for producing codes of impulses in the track and with a diagrammatic representation of a locomotive in the block. Fig. 2 represents one type of current wave form that may be produced in the track and the corresponding voltage wave form induced in the receiver. Fig. 3 represents another form of track wave and the corresponding voltage wave form in the receiver. Figs. 4-9 are schematic representations of various codes that may be used. Fig. 10 is a schematic illustration of as much of a simple form of receiving apparatus and receiving circuit on the

locomotive as is necessary for a clear understanding of the invention by one skilled in the art. Fig. 11 is a schematic illustration of one form of the track code controller symbolized or diagrammatically shown at 3 and 6 of Fig. 1.

In Fig. 1, 1 are rails bonded to form each a continuous conductor from end to end. 2 are insulators electrically separating the rails 10 of the one block from adjacent blocks. 3 is a circuit connection between the two rails at the entering end of the block and will usually comprise a relay or relays for signaling and other purposes. 4, as indicated, is 15 a symbol for a locomotive carrying, ahead of the front wheels, inductors 5, more clearly shown in Fig. 10 in their relation to the rails 1. 6, as indicated, is a track current controller. Its function is the setting up of 20 suitable codes of impulses in the rails of a block as determined by the condition of the track ahead. As is well known such controllers comprise a source of electrical current, either in the form of a generator or 25 battery or in the form of power lines from a distant source of current supply, and an interrupter, switch, pole-changer, reversing device, rheostat or the like for making, breaking, reversing or otherwise varying the current 30 flowing in a given circuit. Reasonably reliable speed controlling or time measuring means is also comprised in any such controller. The controller 6 need not even be situated near the track, but the conductors 35 connecting it thereto may be extended so that one controller may serve a number of sections of track. The connection between the controller and the track circuit may be inductive—as through a transformer—instead of 40 conductive as illustrated. In fact any well known means may be used to produce a current flow in the track of the character described. Merely to fix the ideas a suitable controller and a cooperative track relay are 45 shown in Fig. 11 and will be described below.

The upper line of Fig. 2 is a graph or current-change curve in which the horizontal dimensions represent time and the vertical dimensions above the line O—O represent 50 positive current and the vertical dimensions below the line O—O represent negative current. The lower line of Fig. 2 shows the corresponding voltage for the receiver and the two together illustrate how a gradual increase of current in the track induces a very small steady voltage in the receiver and how the abrupt dying out of the current in the track induces in the receiver a relatively high but brief voltage wave corresponding in sign 55 to the original track current.

Fig. 3 is a graph substantially identical with that of Fig. 2, also showing track and receiver curves and illustrating how abrupt reversals of current direction in the track 60 induce in the receiver relatively strong but

brief impulses corresponding in sign to the track current impulse.

Fig. 4 symbolizes a preferred code of track impulses (or we may read them as in the receiver) which will permit a locomotive carrying the receiver of Fig. 10 to travel at any speed at which the engineer may desire to run without automatic interference. This code I have termed the "clear" or "unlimited" code. In this figure and in Figs. 5-9 inclusive, horizontal dimensions represent, in a general way, time; the signs + and — above and below the line O—O represent each one an impulse of positive or negative polarity and are with equal logic in most cases understood to symbolize either or both the impulses in the track or in the receiver.

In the code of Fig. 4, "clear" code, it will be seen that the time represented by the dimensions A is relatively brief between each impulse and the next effective one. In this case, and because an unbiassed polarized relay is utilized, the next effective impulse is the next of the opposite polarity. Without limitation to any definite value for this time, and merely to fix the ideas, this period may be of the order of one second. It must be understood that, while this code is the only "clear" code illustrated, and is the preferred one for reasons of simplicity, any timed sequence of impulses will be satisfactory as a "clear" code in which the intervals between effectively received impulses are never longer than the suitable time A. Thus a regular code of two positive impulses followed by two negatives and repeated indefinitely at, say, two second intervals would be the equivalent of the illustrated "clear" code of Fig. 4 assuming the polarized relay to be of the unbiassed type. If the polarized relay 23 of the receiving circuit Fig. 10 is biassed, which is readily done by adjusting its armature nearer to one pole than to the other so that said armature has a normal position of rest when no current is flowing through coils 21 and 22 and does not, as I prefer it to do, remain on either side according to its last operation, then the "clear" code may be composed entirely of impulses of the one polarity. Such impulses could be of the type of the positive track and receiver impulse forms of Fig. 2. They would have to be repeated at intervals sufficiently brief, i. e. at intervals not exceeding a time A found suitable to properly operate the receiving circuit.

Fig. 5 illustrates a code of impulses which, in cooperation with the receiving apparatus and circuit (Fig. 10) carried on the locomotive, will act to prevent the engineer from continuing at a speed higher than a certain predetermined limit when the locomotive is in a block in the rails of which this code is being produced. While the details of the receiving circuit may be modified in many ways, in the disclosed receiving circuit, the

code of Fig. 5 will automatically apply the brakes under certain conditions within a brief period after this code has begun to act upon the receiver. One of these conditions is that the train be moving faster than a certain speed. Another is that the engineer has not by a manual application of the brakes already started to reduce the speed of his train. The above is merely explanatory of the function of this code of Fig. 5 and the detailed conditions and operation will be more particularly described below. This code and those having the same general speed limiting function are herein termed "caution" codes.

It will be observed that the time B in the code of Figs. 5-8 is the longest time between effective impulses. With an unbiased polarized receiving relay the time between effective impulses is the time from the first impulse of one polarity to the first of the opposite polarity. Time B is several times longer than the time A of the "clear" code. Merely to fix the ideas, we may take time B as of the order of seven seconds. It should be noted that one of the merits of timed impulse codes for controlling train speeds is that the times B may be largely varied according to the speed limit desired by different railroads, in different portions of one railroad, in different blocks behind an occupied block, even if desired at different times of the day or of the year, or for other reasons as may be dictated by experience.

With a biased polarized receiving relay this code might equally well be composed of nothing but positive impulses, e. g. of the type of Fig. 2, occurring at proper time intervals B. No "clear" or "caution" codes of this type i. e. composed solely of impulses of one polarity, have been illustrated in the drawings for the reason that the polarized relay 23 shown in Fig. 10 is not biased, i. e. has a balanced adjustment and remains in the position to which it was last operated. Such unipolar "clear" or "caution" codes would therefore not cooperate with the receiver shown. The possibility of using codes of one polarity is pointed out here merely to emphasize the fact that the intervals of time between effectively received impulses are the most important distinguishing characteristics of these different codes.

Fig. 6 illustrates a "caution" code identical with that of Fig. 5 except that the first positive impulse induced in the receiver is succeeded by a series of positive impulses having no effect whatsoever on the preferred receiver, and the first negative impulse is likewise succeeded by negative impulses without effect. This variation is illustrated to show the flexibility of the system and while of no advantage in the practice of this present invention as shown might be preferable to that of Fig. 5 for use in connection with certain types of track current control or local signaling circuits or with certain types of track relays. Thus if the track current-change curves of Fig. 2 are used the code of Fig. 5 would involve a relatively long time with no current in the rails 1 and through the connection or track relay 3. If we suppose 3 to be a signaling relay requiring to be held up during the "caution" code, track impulses of the form of Fig. 2, repeated as in the code of Fig. 6, might with certain types of relays more readily accomplish this end for the signal engineer. The relationships between the codes in the one block and in the block behind or before and the means of producing these relationships may be greatly varied within the spirit of this invention. The above remarks as to the possible superiority of the code of Fig. 6 under certain circumstances are merely illustrative of the inherent flexibility of the present track current code system.

Fig. 7 illustrates a third "caution" code in which the time B, as before, is the period from the occurrence of the first impulse in the receiver of one polarity until the occurrence of the first of the opposite polarity. It differs from the codes of Figs 5 and 6 in that a brief period A is interposed between the longer periods B, and is typical of a whole class of possible, but not further illustrated, codes in which periods of "clear" code are regularly interrupted by relatively long "caution" periods or code pauses B.

Fig. 8 illustrates a code identical with that of Fig. 7 except that the polarities are reversed and with the further exception that the times B are filled with repeated impulses of the one polarity after the manner of the code of Fig. 6.

Fig. 9 illustrates four of the many possible varieties of "stop" codes. These are codes which, cooperating with the receiver of Fig. 10, force the engineer to apply his brakes and keep them on until his train comes to a dead stop under penalty of the brakes being automatically applied. The one essential characteristic that the four codes illustrated in Fig. 9 have in common is that, with the exception of a single first impulse in several cases, they produce no effect whatever upon the receiving relay. They are, to all intents and purposes, the same in effect on the receiver of Fig. 10 as indefinitely long "caution" periods or code pauses B of the various types shown in the "caution" codes of Figs. 5-8. The first code shown in Fig. 9 is a series of repeated positive impulses only, i. e. necessarily impulses of the general type of Fig. 2. The second code of Fig. 9 is a series of repeated negative impulses. The third shown is a long continued direct current flow in the track in a positive direction, i. e. an indefinitely extended wave of the type of the track wave of Fig. 3. A continued flow in the negative direction in the track would be another possibil-

ity. The fourth "stop" code shown in Fig. 9 is merely dead track, i. e. without current of any kind. Obviously, the third and the fourth are identical as far as the impulses induced in the receiver are concerned, and it will be seen when the receiver circuit of Fig. 10 is described, that all four are identical as far as effects on the polarized receiving relay are concerned.

10 The advantage of the last two "stop" codes will be particularly apparent when it is considered that the failure of the source of track current energy S of Fig. 1, the failure of the track current controller 6 of Fig. 1, the opening 15 of the track circuit or the short circuiting thereof, at any point between the locomotive and the controller 6, all act to produce this form of "stop" code. Likewise any failure of the receiving mechanism of Fig. 10 to receive 20 the impulses that may be in the track, has the same effect on the train control mechanism as these last two "stop" codes. There is a similar advantage in the choice of the first two "stop" codes illustrated in Fig. 9 in that 25 any failures in the track current controller effecting one polarity only, or any failures in the receiver of Fig. 10 such that it can receive or amplify one polarity only, result in the equivalent of the first or the second "stop" 30 code of Fig. 9. To those acquainted with the train control art the value is obvious of this choice of codes whereby failures produce the effect of a more precautionary signal.

In Fig. 10, 1 are the rails of Fig. 1 shown 35 in cross section, 5 the inductors or inductive receivers each comprising an iron core mounted on the locomotive in a position as near to the rail as the necessary clearances of railroad usage will permit. These cores are each 40 surrounded by a winding 7 and these two windings are preferably connected in series, and also in such a manner that the electromotive forces, generated in the windings 7 by changes of current in the rails 1, shall reinforce 45 each other. The relative direction of flux in the two inductors, when the current in the track circuit is in one direction, is indicated by arrows on the dotted lines 8. From the inductors two conductors 9 and 10 lead 50 respectively to the filament and grid of a three-electrode electron tube 12. 11 is a filament heating battery or so called "A" battery; 13 is the plate circuit battery usually 55 called the "B" battery. The plate circuit is completed by conductors 14 and 15 through the primary 16 of a transformer. 17 is the iron core of this transformer. 18 is the secondary; conductors 19 and 20 complete the secondary circuit through the windings 21 60 and 22 of a polarized relay 23. As illustrated this relay is electromagnetically polarized by energy from a battery 24 and a polarizing winding 25, but a permanent magnet may be used in place of an electromagnet as a source 65 of polarizing flux. The windings 21 and 22

are wound and connected in such a manner that a current flow in either direction in the secondary circuit 18, 20, 22, 21, 19 tends to produce opposite polarities at the poles 26 and 27. The polarizing flux due to the winding 25 enters the armature 28 substantially at the center and a portion goes to the right hand half of the armature returning through pole 26 and the common frame 23 of the relay. A portion of this polarizing flux goes 75 to the left hand half of the armature through pole 27 and returns through the common frame 23. Thus the flux due to the polarizing coil is in the same direction through both poles 26 and 27. The preferred adjustment 80 of this relay is such that the pull of these two poles is substantially equal when tongue 29 is held half-way between its two positions of contact with conductors 31 and 32.

At this point it may again be mentioned 85 that if the relay were such that tongue 29, when no current flows in coils 21 and 22, always returned to lie on the same side, it would respond only to impulses of one polarity. If we assume that it lay as actually shown in 90 the drawing, and if we call positive that impulse that will cause it to move to its other position, this makes clear the statement, above, that by biasing the polarized relay of the receiver a track code of impulses like those 95 of Fig. 2 but of one polarity will be operative. As will be better understood after the whole operation of this receiving structure has been described, a very refined and exceptionally quick design for the left hand 100 quick-acting slow-release relay 34 would in this event be required. As stated above the biased polarized relay would be less sensitive. The change offers no sufficient advantages over my preferred structure so far as 105 I can perceive to compensate for these two disadvantages. It is possible again as stated above, that for certain track circuit purposes a code of one polarity would be a simplification.

Resuming the description of the structure as shown, the flux due to currents in the windings 21 and 22, being of opposite sign in the two poles, oppose the polarizing flux in the one pole and aids it in the other. Due to the well known law that the pull between a pole and an armature is proportional to the square of the average density of the flux multiplied by the effective cross section of the flux, this type of relay can be made responsive to very 115 small impulses by increasing the polarizing flux. It is for this reason that electromagnetic polarizing means are preferred. All of this polarized relay construction is of course well known in the art.

The armature 28 of the polarized relay carries a light tongue 29 which is grounded at 120 and which makes contact in the one position to conductor 31, in the other to conductor 32. This armature is pivoted on a knife 125

edge 33 and in the absence of current through windings 21 and 22, retains the contact which it last made with some firmness due to the polarizing flux which holds the armature strongly to the nearer one of the poles 26 or 27. In the diagram more polarizing flux is temporarily passing through pole 27 than through pole 26 because of the temporarily larger air gap at pole 26. The tongue 29 is therefore firmly held in contact with conductor 31.

Polarized relay tongue 29, due to received and amplified impulses of alternate polarity closes the circuit alternately from ground 30 through conductor 31 or 32 and either one of two quick-acting slow release relays 34 to battery and ground. Relays 34 may be of any suitable construction well known in the art but are very simply and preferably made of the simplest D. C. relay form with the addition of a heavy copper collar or sleeve 35 which, acting as a short circuited secondary, renders the action of the relay sluggish, more especially on releasing. By a suitable adjustment and by using a proper amount of energy in the coils of these relays, they can be made much slower in releasing than in attracting their armatures 36.

The armatures 36 of quick-acting slow-release relays 34, when these relays are energized, close a series circuit from ground through the two armatures 36 and their two front contacts 37, conductors 38 and 67, the extreme left hand contact of relay α , conductor 39 and the left hand winding of relay 40 to battery and ground. A branching circuit 41 from conductor 67 includes a green signal lamp 42 normally in parallel with the left hand winding of relay 40.

Relay 40 is shown with two armatures, but this is done for simplicity in the diagram. This relay and those like it in the drawing are preferably of one of the well known D. C. types having an armature closing, when energized, two or more separate circuits. For brevity I shall hereafter refer to the right and left hand armatures just as shown on the drawing. Relay 40 has a right hand winding connected—aiding the left hand winding—through the right hand armature when 40 is energized and then through conductor 43 to a wiper 44 which bears on an interrupter 45. Interrupter 45 has a relatively short insulated segment and a grounded conducting segment. It revolves in a clockwise direction as viewed in the drawing, and is carried by or operated from a wheel or axle of the locomotive. A second wiper 46 bears on interrupter 45 at substantially 180° distance from wiper 44 and feeds ground to certain relay armatures through conductor 47 as will be explained below.

The left hand armature of relay 40 is grounded and, when relay 40 is energized, closes the circuit to conductor 48 through the right hand winding of relay 50 to battery

and ground. Relay 50 has a left hand winding of which the circuit is closed from the grounded interrupter 45 through wiper 46, conductor 47 and its own left hand armature to grounded battery when relay 50 is energized. This circuit is of course open at the interrupter when wiper 46 is on the insulating segment. The right hand armature of relay 50 is grounded and, when 50 is energized, closes a circuit containing the left hand winding of relay 60. The relay 60 has a right hand winding the circuit of which is closed when it is energized, through its own right hand armature, conductor 43, wiper 44 and grounded interrupter 45. This circuit is of course open at the interrupter when wiper 44 is on the insulating segment. The left hand armature of relay 60 is grounded and when energized closes a circuit containing the right hand winding of the next counting relay,—not shown,—and so on for an indefinite number of relays. The number of these relays to be used, which I have termed the counting relays, is dependent on the speed limits to be enforced and the length chosen for the code pauses or "caution" intervals B.

For simplicity in the drawings I have shown of this first series of counting relays only the first three designated 40, 50, 60 and the last three designated α , γ , β . It will be clear from a comparison of the figures on the drawings that the relay α is connected exactly like the relay 50, the relay γ is connected exactly like the relay 60, and the last relay β again like relay 50.

Relay α is energized through its right hand winding by the left hand armature of the preceding relay and is periodically energized through its left hand winding by its own left hand armature and the wiper 46 of interrupter 45. The grounded right hand armature of relay α closes, when the relay is energized, an additional circuit through conductor 49, and yellow signal light 51 to grounded battery. Relay γ is, by conductor 68, connected to the first relay 40 α of a second or continuation series just as relay 50 is to 60. Relay 40 α is succeeded by another relay (not shown), and so on to the last relay β . For simplicity of the diagram only the first and the last relays 40 α and β , are shown of this second series.

Relay β by its grounded right hand armature and contact holds energized solenoid 53 over the circuit including conductor 52, the winding of 53, solenoid locking spring 54, conductor 55, to grounded battery.

The solenoid 53 while energized maintains the valve rod 56 and valve 47 in the upward position shown. 58 is the body of an electro-pneumatic valve which comprises solenoid 53, valve rod 56 and valve 57 and is shown in section. 59 is an air pressure connection from the brake controlling air line of the train. It is assumed that a reduced pressure

in this air line applies the brakes. 61 is a tension spring to assist gravity in opening the valve 57 when solenoid 53 is deenergized. 62 is a manually operable key for closing the circuit of the solenoid when it is deenergized and when in consequence spring 54 is not in contact with conductor 55. 63 is an insulated mechanical connection to a pressure gauge or the like,—not shown,—connected to the air brake system in such a way that if brakes are applied adequately 63 presses against contact spring 64 closing a circuit from ground through conductor 65, through the left hand coil of relay γ to battery. Thus 64 is an alternative to, and in multiple with, the right hand armature of relay α . 66 is a sealed receptacle or box enclosing the electro-pneumatic valve, the solenoid 53, the key 62 and preferably also enclosing the pressure gauge contact elements 63, 64. This receptacle or box and its seal may be of any well known construction. Its purpose is to prevent the engineer from closing the electro-pneumatic valve if it once opens without leaving proof that it has been open.

Assuming the locomotive 4 to be receiving the "clear" code of Fig. 4 or any equivalent code comprising continuous sufficiently rapid alternations of positive and negative impulses in the track, the operation is as follows: The current flow in the track, whether gradually increasing as diagrammed in the upper line of Fig. 2 or steady as in the upper line of Fig. 3, sets up flux about the rails a portion of which, 8, is led by the iron cores 5 of the inductors through the windings 7. The abrupt interruption or interruption and reversal of the current flow in the track causes the sudden dying out or dying out and reversal of the flux 8. This sets up in windings 7 a relatively high electromotive force the relative instantaneous polarity of which is dependent upon the original direction of current flow in the track. This electromotive force raises or lowers the potential of the grid of the three-electrode electron tube 12 and causes a corresponding sudden increase or decrease in the plate current flow from battery 13 through filament and plate of 12, conductor 14, primary winding 16, and conductor 15. It will be noted that, as is well understood by those skilled in the art of amplification by electron tubes, this current will vary in magnitude but not in direction. By the use of the transformer 16, 17 and 18 these sudden increases and decreases of the plate current are again converted into positive and negative impulses in the circuit 18, 19, 21, 22, 20.

As explained above, these positive and negative impulses through the windings 21 and 22 of the polarized relay 23 throw the contact tongue 29 from side to side, alternately energizing relays 34. Relays 34 are designed to maintain their armatures attracted for a brief period after the circuit of their wind-

ings is open and this period must be somewhat greater than the period A between alternate impulses of the code of Fig. 4 or any equivalent "clear" code that may be used. Relays 34 are also designed to attract their armatures 36 in a period somewhat less than the period A. Thus when the code of Fig. 4 or an equivalent is being produced in track 1, and when in consequence tongue 29 of polarized relay 23 is alternately in contact with conductors 31 and 32 for equal periods of duration A, both relays 34 maintain their armatures 36 attracted and a circuit is closed from ground through these armatures, through conductor 41 and green lamp 42 to battery, and in parallel with the latter, through conductor 67 left hand armature of relay α , conductor 39 and left hand winding of relay 40 to battery. The green signal light burns steadily and relay 40 remains energized. Relay 40 by its left hand armature maintains relay 50 energized. Relay 50 by its right hand armature maintains relay 60 energized and so on to the end of the series, all the relays 40 to α remaining energized.

The right hand armature of relay α closes the circuit of the yellow signal lamp 51, which burns steadily. Relay α , by its right hand armature, also maintains closed the circuit including conductor 68 of the left hand winding of relay 40 α . Relay 40 α holds energized the next relay, and so on to relay α^a , which by its grounded right hand armature and through conductor 52 maintains solenoid 53 energized through spring 54 and conductor 55 to battery. Solenoid 53 holds closed the valve 57 and air from the brakes cannot escape from valve chamber 58.

The only moving elements in the circuit on the locomotive under these conditions are the armature and tongue 28 and 29 of polarized relay 23 and the continuously revolving interrupter 45 connected to a locomotive wheel. This may be called the normal or locked condition of the receiver.

Assuming, now, the locomotive to be on track containing a caution or speed limit code of one of the types illustrated in Figs. 5-8 or equivalent, the operation is as follows:

Omitting the repetition of the detailed operation of receiving, amplifying and transforming the impulses, it will be clear from the preceding explanation that at the beginning of one of the "caution" code intervals, or code pauses, designated by the letter B in Figs. 5-8, polarized relay tongue 29 will be positively thrown to one side or the other and will there remain until the end of the period B. The period B is much longer than the period during which relays 34 can,—without current in their windings,—maintain their armatures attracted. One of these relays 34 will therefore, after the lapse of a time somewhat greater than A, release its armature and open the circuit both of the green

lamp 42 and of the left hand winding of relay 40. The green lamp will go out. Relay 40 will be maintained energized by its right hand winding for a period varying from zero to nearly the time of a complete revolution of interrupter 45, but clearly will be de-energized when wiper 44 goes over insulating segment 45. It will then unlock itself by its right hand armature so that it cannot be again re-energized by the circuit from ground through wiper 44 and conductor 43. The left hand armature of relay 40, being released, deenergizes the right hand winding of relay 50 which remains energized by its left hand winding until wiper 46, in its turn, goes over the insulating segment of 45. Relay 50 is then unlocked and deenergizes one winding of 60 which is next unlocked by interrupter 45, one-half revolution later, and so on. The relays of the series are thus unlocked one after the other at intervals measured by a half revolution of interrupter 45. The rate at which the whole series of relays is unlocked is therefore directly dependent upon the speed of the train.

If we assume the speed of the train to be higher than the limiting speed predetermined by the caution code in use and if we assume that the engineer is negligent and has not noted the caution signal on the roadside semaphore, if there is one, and has likewise not seen the extinction of the green signal light in the cab of the locomotive and acted promptly, then relay α , which is the second from the last relay of the first series, will release its right hand armature, extinguishing the yellow signal light 51. Relay γ and relay α are next unlocked. Relay α by its extreme left hand armature opens the connection between conductors 67 and 39 and makes it impossible for relays 34 to reenergize the left hand winding of relay 40. At this point of the operation, and by this action of relay α , a prompt brake application is irrevocably determined.

There remains the question whether it shall be an automatic application or a manual one. If the manual application is delayed until the second series of relays, 40^a— α , are all deenergized, the application will be automatic. In this case, when deenergized, relay α by its right hand armature removes ground and releases solenoid 53. Valve 57 opens, aided if necessary by spring 61. Pressure in the brake air line is reduced and brakes go on. Contact 54, 55 is opened and the circuit through the solenoid cannot be restored unless box 66 is opened. This will leave a record as for instance a broken seal. Key 62 is provided within the box as an easy means of restoring the circuit for reenergizing solenoid 53 when the box is open.

Preferably a reduction of pressure in the brake air line sufficient to apply brakes adequately, whether due to the automatic open-

ing of valve 57 as just described or to the opening of a manually operated valve, and acting through any well known pressure gauging means, closes a circuit as follows: from grounded spring 64, through conductor 65, left hand winding of relay γ to battery and ground. By this circuit relay γ , if deenergized, will be reenergized and will reenergize relay α , this in turn reenergizing 40^a and so on till relay α is reenergized. This, as explained, cannot however restore the electropneumatic valve because the solenoid circuit is open at contact 54, 55. Thus the engineer cannot release the brakes without unlocking the box. But if this reenergizing process is initiated by a manual application of the brakes, i. e. if just before relay α and solenoid 53 are unlocked the circuit:—ground, 64, 65, right hand winding of relay γ to battery and ground—is closed the deenergization and unlocking of the solenoid will be forestalled.

Instead of pneumatic pressure or other pneumatic means to close the contact 64, 65 when brakes are applied, any well known or obvious mechanical electrical or other means may be employed. This is a matter in which the nature of the braking system in use will be controlling, and one that will offer no difficulties to those skilled in the art. As stated above, contact 64, 65 is only preferably located in sealed box 66. It may be more convenient to locate it elsewhere. It should be so devised as not to be operable except by a brake application of predetermined force or greater.

At the end of the caution cycle B the polarized relay tongue 29 swings to the other side, the deenergized one of relays 34 becomes energized, and the circuit of the green lamp is again closed. If at this time relay α is energized the circuit of the right hand winding of relay 40 is also completed. Relay 40 by its left hand armature energizes relay 50, relay 50 energizes 60 and so on with extreme rapidity to the end of the deenergized series, i. e. down through relay γ in the extreme case, these relays being quick-acting. The yellow lamp will again start to burn.

But another caution cycle B may begin at once and one of the relays 34, after a certain period a little longer than A, releases its armature, the green light is extinguished, and the process of successively deenergizing relays 40, 50, . . . α . . . γ again begins. It is thus clear that as long as the speed of the train is such that interrupter 45 deenergizes all of the relays 40 . . . α before the end of caution cycle B, the green lamp will flash on very briefly and the yellow lamp will flash off very briefly.

If we assume that the engineer noted the roadside caution signal or the first extinction of the green light in the cab and manually applied the brakes before interrupter 45 had

deenergized the whole series of relays, he will close the spring 64 to conductor 65 and thereby will maintain relays $y, z \dots z^a$ and consequently solenoid 53 all energized and valve 57 closed. This is the case even if relay z had released its right hand armature before the fresh impulse was received from the track. As long as he maintains the brakes on with sufficient force, contact 10 64, 65 is closed and the automatic application of brakes by the release of solenoid 53 is avoided. When he has reduced the train speed to a point where the interrupter 45 cannot count down all of the relays $40 \dots z$ 15 before a fresh impulse at the end of the caution cycle B, by reenergizing the deenergized relay 34, sets them all up again, he may if he wishes release the brakes. He will know that he has sufficiently reduced the train speed 20 to release brakes, and with a little margin of safety, by the cessation of the flash—briefly off—of yellow lamp 51. This margin of safety is provided by connecting lamp 51 to a relay one or two earlier in the series 25 than the relay z . If, without this margin of safety, he should unconsciously allow the train to speed up a very little he might receive an automatic application of brakes which would not be heralded by earlier flashings of yellow lamp 51. He would therefore 30 require accurate speed determining means and would also be forced to remain well on the safe side of the speed limit.

It will be noted that the cab signal lamps 35 42 and 51 are not affected by the restoring of relays $y \dots z^a$ by any brake application. The relays $40 \dots z$ are still subject to their two conflicting controls, the polarized relay 40 by way of relays 34, 34 tending at intervals to restore them and the interrupter 45 tending steadily to deenergize them one by one. Thus the lamps continue to give significant 45 indications as to the code that is being received—particularly lamp 42,—and as to whether the train speed has or has not been brought within the required limit—particularly lamp 51.

In view of the foregoing explanations, the action of any "stop" code will be immediately clear. One of the relays 34 releases its armature permanently or until the "stop" code is succeeded by a "caution" or "clear" code. The green lamp goes out permanently. The relays are counted down and are not 55 restored by the polarized relay, since no effective track impulses are coming in. The yellow lamp goes out permanently. If the brakes have not by this time been manually applied, an automatic application of brakes occurs when relay z^a is deenergized. Assuming that the engineer has applied the brakes 60 early enough to forestall the automatic application thereof, as long as both the green and yellow lights remain out and if the train 65 is still moving he may not release the brakes

under penalty of their being automatically applied almost at once.

In this connection it may be remarked that from a practical standpoint some railroad operating men may prefer, instead of using an absolute "stop" code for indicating danger ahead, to use a code of the type of the "caution" codes but in which the pause B is so extended as to limit the train speed to 5 or 10 miles an hour. This will allow the engineer to advance slowly in a danger block 75 with his brakes off.

The reason for causing a brake application to first energize relay y instead of relay z —which is the one that directly controls the circuit from the slow-release relays 34, 34 to relay 40—is that the train will often be stationary in a "stop" block with wiper 46 on the insulating segment of the interrupter. If conductor 65 were brought directly to the right hand winding of relay z any application of brakes would pull up z but with the above conditions existing z would again be deenergized upon release of brakes. This would force the engineer to stand in a "stop" block—or even in an "occupied" block, which has the same effect on the receiver—with his brakes on all the time. He should be permitted to release them. And the reenergization of relay y , prior to z , by the brake application assures that relay z , at least, will remain energized when the contact 64, 65 is opened. For obviously the insulating segment of 45 cannot be under both wipers 44 and 46 at the same time. 100

In Fig. 11, S is a source of electrical energy,—see Fig. 1— and is here shown as a battery including a protective resistance and a fuse F. The source S might equally well be a generator or power lines fed from a distant source. To cooperate with the structure of the track current code controller 6 shown, S must be a source of direct current. 105

My invention, however, may be variously practised, as was suggested above, and among other variations S may be a transformer or set of transformers or of power lines selectively delivering (conductively or inductively) into the track circuit series of current waves of substantially the characteristics shown in Fig. 2 and of the proper sequence, polarity and timing to constitute the required code for the conditions of the moment. In other words the code currents may be produced at a distance,—instead of locally by a battery and interrupters as shown and as I am about to describe in detail,—transmitted over wires to the different controllers 6 along the roadbed, and selectively fed by them to the track circuits in substantially the same manner as, in Fig. 11, I feed the locally generated codes. 110

In controller 6, shown in Fig. 11 surrounded by a dotted line, 69 is an interrupter or rather a reverser or pole-changer fed by the battery leads 71, 72,—respectively + and —, through 115

wipers 73 and 74 bearing on collector rings 77 and 78. Wipers 75 and 76 bear alternately on the + and the - conducting segments of reverser ring 79. The insulation between these 5 segments is wider than the bearing surface of 75 and 76 so that they are both simultaneously insulated from the battery S for a very brief instant. Wipers 75 and 76 and the leads 81 and 82 therefrom thus deliver brief periods 10 of steady current alternating in polarity rather than ordinary or sine wave alternating current. The frequency of the alternations is determined by the speed of shaft 83 which I have marked "fast" in the drawing. 15 Reverser 69 produces "clear" codes.

Shaft 83 may be driven by any suitable motor,—e. g. an electric motor drawing energy from source S,—and this motor must have quite constant speed. A small D. C. motor 20 with governing means to compensate for voltage changes would be suitable. Shaft 83, being properly geared to the motor, revolves at such a speed that one half revolution takes the time A of the "clear" code.

25 84 is an exactly similar reverser, except that the speed is such as to produce "caution" code. It need not be further described. Conductors 85 and 86 then deliver slow reversed direct current according to the code of Fig. 5 30 and with wave forms substantially like those of the upper line of Fig. 3. The shaft of reverser 84 is preferably geared, in proper speed relation to shaft 83, to the same motor.

The wave forms of Fig. 3 show no break or 35 bend in the curve between the interruption of, let us say, a positive current flow and the establishment of negative flow. This is possible, by reversers like 69, if the time during which wipers 75 and 76 are entirely insulated 40 from the battery is more brief than the time necessary for the current flowing in the track circuit to decay to zero. This requires, if accidental short circuits are to be avoided, either a very close adjustment of the widths of the 45 insulation and of the wipers, or a relatively large surface speed of reverser ring 79. The latter is preferable and obtainable by making the diameter of 79 large in relation to the width of wipers 75 and 76.

50 It is noteworthy, however, that using as I do in Fig. 10 an unbiased polarized receiving relay, this refinement is not necessary. If, sometime after current in the one direction has been interrupted, current in the opposite 55 direction is sharply set up in the track, the result as far as the receiving circuit on the locomotive is concerned is merely that two impulses of the same polarity are received in rapid succession. The first will have practically always the higher voltage and the shorter duration and will operate the polarized relay. The second will have no effect.

Moreover, other forms of reversing devices, with a quick spring or magnetic action are 60 well known and can be equally well used.

The commutator and carbon brush type I find preferable from the standpoint of general durability and reliability of contact. In any case should either reverser slow up, stick, 70 lose contact, or be short circuited and blow the fuse F, the code fed to the track will enforce a lower train speed, or produce the effect of "stop" code.

87 is a polarized relay, biased—and it is shown biased by a spring 88, though it may be 75 biased by unbalanced polarizing flux—and for economy only shown with a permanent polarizing magnet 89. Its armature is grounded. It is connected across the entering end of block or section of track No. 1. It 80 constitutes, together with conductors 91, 92 the circuit connection 3 of Fig. 1, which completes the track circuit for this block. The track circuit in each block is normally closed through the windings of relay 87, but when a 85 train enters the block, the track circuit is closed through the wheels and axles thereof.

In Fig. 11, though the rear or entering ends of two blocks Nos. 1 and 2, are visible, the drawing of relay 87 has not been repeated for 90 block No. 2, and conductors 91^a, 92^a leading to another and to be imagined similar polarized relay across block No. 2 are merely indicated ending in arrows. This is also the treatment of the two visible front or exit ends of blocks Nos. 2 and 3, and of the conductors 93, 94 or 93^a, 94^a feeding them from code controllers 6. Only controller 6 feeding block No. 2 is shown.

Tongue 95 of relay 87 alternately makes 100 contact, either rapidly or slowly, on conductors 96 and 97, if in block No. 1 the existing code is "clear" or "caution". Two extra slow relays 98 are thus energized by tongue 95, one through conductor 96 and one through 105 conductor 97. Relays 98 are shown equipped with heavy copper collars, to indicate slowness. They are preferably of a mechanically retarded type, because of the expense of making an electrically retarded relay as slow 110 as these require to be, if the "caution" interval B is taken of the order of seven seconds as suggested above. The preferred retardation if such long code intervals are chosen is 115 of a well known type involving angular acceleration of a balanced mass or flywheel by a relatively weak force applied by the attracted armature, and is such that the energy of successive impulses is largely stored in the mass. A weak spring or light weight opposes 120 the armature attraction. If, however, more rapid "caution" codes are chosen, electrically sluggish relays are suitable, and can be produced at reasonable expense.

When, therefore, either "clear" or "caution" code is in block No. 1, extra slow relays 98 attract and hold attracted their armatures and a circuit is closed from battery through their armatures in series, through conductor 99 and the winding of relay 101 to ground. 125 130

Relay 101 attracts its two armatures and connects the leads 81, 82 which yield "clear" code, to the track feed wires 93 and 94 of block No. 2. Thus "clear" or "caution" in one block establishes "clear" in the block behind.

Let us assume that in block No. 1 the "stop" code is set up. As the polarized relay 87 is, more or less fortuitously, shown biased to respond to positive current, it is necessary to choose as the "stop" code to cooperate therewith the one shown on the third line of Fig. 9, namely, continued steady current in the positive direction. Oppositely biasing the relay 87 would require using for "stop" code a continued negative current. Assuming then a continued positive flow in block No. 1 and therefore through conductors 91, 92 and the winding of relay 87, the right hand extra slow relay 98 is held energized, but the left hand relay releases its armature. It is readily seen that a circuit is thus closed energizing relay 102 and thereby applying to feed wires 94 and 95 the "caution" code always in leads 85 and 86. Relays 101, 102 and 103 must be relatively quick to release, and slow to operate, in order that two codes shall not be fed simultaneously with probable short circuits. We now have "stop" code in block No. 1 causing "caution" code to be fed to block No. 2. This in turn will cause "clear" code to be fed to block No. 3.

Assume now that block No. 1 is occupied and that the entering end is therefore dead. Relay 87 lies as shown in Fig. 11. Relays 98 stay as shown, and a circuit is set up energizing relay 103 and feeding steady current in the positive direction from battery leads 71, 72 to feed wires 93, 94 and to track of block No. 2. This is the "stop" code chosen. We thus have the occupied block No. 1 setting up "stop" code in block No. 2. This in turn, as detailed above, sets up "caution" code in block No. 3, which again sets up "clear" code in block No. 4. And "clear" code in block No. 4 reproduces itself in No. 5 and so on.

What I claim is:

1. In a train control system, a track section, a vehicle movable thereon, means to produce in said track section discrete electrical impulses on a plurality of different time interval patterns corresponding to a plurality of different operating conditions for said track section, and a receiver on said vehicle having a group of elements responsive to individual discrete impulses in the track section and having another group of elements responsive to their time interval pattern.

2. In a train control system, a track, vehicles on said track, means to produce in said track a code of abrupt electrical current changes occurring at predetermined intervals, a receiver on one of said vehicles responsive to abrupt current changes in the track and comprising amplifying means, a relay responsive to an individual abrupt current change in

said track, and a train control means dependent upon said relay.

3. In a train control system, a track, a vehicle thereon, a wheel of said vehicle rolling on said track, means to set up timed current changes in said track, a time marking receiver element on said vehicle inductively operated by said timed current changes, a travel-indicating receiver element comprising said wheel, and train control means jointly dependent upon said time marking element and upon said travel-indicating element.

4. In a train control system, a track, vehicles thereon, means to produce in said track a plurality of codes of discrete electrical waves differing in their timing, a receiver on one of said vehicles variably responsive to the different codes, a relay in said receiver operated by individual ones of the discrete electrical waves, a travel-indicating device and a vehicle-control means jointly dependent on said receiver, said relay, and said travel-indicating device.

5. In a train control system, a track, a vehicle on said track having a wheel rolling thereon, a means to produce in said track timed discrete electrical impulses, a receiver on said vehicle for receiving the timed impulses and responsive to single discrete ones of said impulses, an interrupter operated by the wheel of said vehicle, a series of relays successively controlled one after the other by said interrupter in such a manner that a definite group of relays corresponds to each cycle of said interrupter, and means whereby said series of relays are controllable substantially as one group by said receiver.

6. In a train control system, means for producing predetermined cycles of abrupt current changes in a track, inductive receiving means on a vehicle wherein brief inductive impulses are generated by the abrupt current changes in the track, an amplifier, a polarized relay on said vehicle operable by an individual brief inductive impulse generated in said receiver, and a train control circuit dependent upon the cycles of operation of said polarized relay.

7. In a train control system, a track, a vehicle on said track, a track code generator producing timed cycles of electrical impulses in said track, a receiver on said vehicle operating in response to individual impulses in said track, a wheel on said vehicle, means to count the revolutions of said wheel whereby distance is measured, means to compare the times of operation of said receiver and of said means to count whereby speeds of said vehicles are determined, and a train control means operable by said means to compare.

8. In a train control system, a track, vehicles on said track, a generator setting up in said track vehicle signaling codes comprising abrupt electrical current changes of predetermined sign and at predetermined in-

5 tervals, a vehicle signaling receiver in which brief electrical impulses are induced responsive to the abrupt current changes in said track, a relay selectively operated by said receiver in accordance with the polarity of the brief electrical impulses induced therein, a source of electrical energy on said vehicle, a train speed controlling means energized from said source, and means whereby said 10 train speed controlling means is rendered temporarily ineffective by the operation of said relay.

9. In a train control system, a track, a vehicle on said track, means producing in said 15 track timed impulses, an inductive receiver on said vehicle, an amplifier on said vehicle, a polarized relay on said vehicle operable by individual impulses in said track, a slow release relay operated by said polarized relay, 20 a vehicle wheel, an interrupter operated by said wheel, and a series of counting relays energized as a group by said slow-release relay and individually deenergized one after the other by said interrupter when said slow- 25 release relay is deenergized.

10. In a train control system, a track, a vehicle on said track, means producing in said track timed impulses, an inductive receiver on said vehicle, an amplifier on said vehicle, 30 a polarized relay on said vehicle operable through said receiver and said amplifier by individual impulses in said track, a slow-release relay operated by said polarized relay, a vehicle wheel, an interrupter operated by 35 said wheel, a series of counting relays energized as a group by said slow-release relay and individually deenergized one after the other by said interrupter when said slow-release relay is deenergized, electromagnetic 40 brake control means, and a train control contact on one of said counting relays to control said electromagnetic brake control means.

11. In a train control system, a track, a vehicle on said track, means to produce in said track a code of electrical currents having recurring cycles of change whereby time is measured, a receiver on said vehicle responding to each cycle of change, a device registering distance on said vehicle, and means for resetting said device operated by said receiver.

12. In a train control system, means to produce in a track electrical currents having recurring cycles of change for indicating time, a vehicle, a receiver thereon responsive to each cycle of change, a device measuring the travel of said vehicle, a means to reset said device operated by said receiver, and means to control the vehicle operated by said device if greater than a predetermined travel is measured by said device before it is reset.

13. In a train control system, means to produce in a track electrical currents having recurring cycles of change for indicating time, a vehicle, a receiver thereon responsive

to each cycle of change, a device measuring the travel of said vehicle, a means to reset said device operated by said receiver, and means operated by said device automatically to check the speed of the vehicle and to produce a distinctive signal on the vehicle if greater than a predetermined travel is measured by said device before it is reset. 70

14. In a train control system, means to produce in a track electrical currents having recurring cycles of change for indicating time, a vehicle, a receiver thereon responsive to each cycle of change, a device measuring the travel of said vehicle, a means to reset said device operated by said receiver, 75 a manual braking means, automatic means operated by said device to apply brakes if greater than a predetermined travel is measured by said device before it is reset, and means operated by the operation of said 80 manual braking means to prevent said automatic means from operating if said manual braking means is operated before said device has measured said predetermined travel.

15. In a train control system, means to produce in a track electrical currents having recurring cycles of change for indicating time, a vehicle, a receiver thereon responsive to each cycle of change, a device measuring the travel of said vehicle, a means to reset said device operated by said receiver, a distinctive signal to declare the starting of said device measuring travel, a distinctive signal operated if greater than a predetermined travel is measured by said device before it is 90 reset, brakes, automatic means applying said 95 brakes after said second signal is given, and manual means operable to apply said brakes and while in operated position preventing said automatic means if operated before said 100 device.

16. In a train control system, means to produce in a track electrical currents having recurring cycles of change for indicating time, a vehicle, a receiver thereon responsive to each cycle of change, a device measuring the travel of said vehicle, a means to reset said device operated by said receiver, a distinctive signal to declare the starting of said device measuring travel, a distinctive signal operated if greater than a predetermined travel 110 is measured by said device before it is reset, brakes, automatic means applying said brakes after said second signal is given, and manual 115 means operable to apply said brakes and while in operated position preventing said automatic means if operated before said device.

17. In a train control system, a track, a vehicle, a receiver thereon responsive to each cycle of change, a device measuring the travel of said vehicle, a means to reset said device operated by said receiver, a distinctive signal to declare the starting of said device measuring travel, a distinctive signal operated if greater than a predetermined travel is measured by said device before it is reset, brakes, automatic means applying said brakes after said second signal is given, and manual means including said second signal to indicate when said device is reset before it has measured the predetermined travel, whereby an indication is given that said manual means may be restored to non-operated position without the operation of said automatic means. 125

18. In a train control system, a track, a vehicle, a receiver thereon responsive to each cycle of change, a device measuring the travel of said vehicle, a means to reset said device operated by said receiver, a distinctive signal to declare the starting of said device measuring travel, a distinctive signal operated if greater than a predetermined travel is measured by said device before it is reset, brakes, automatic means applying said brakes after said second signal is given, and manual means including said second signal to indicate when said device is reset before it has measured the predetermined travel, whereby an indication is given that said manual means may be restored to non-operated position without the operation of said automatic means. 130

- hicles on said track, a track controller system successively to set up in said track currents in two directions and abruptly to terminate them in predetermined cycles, a receiver on one of said vehicles wherein cycles of brief impulses of two polarities are induced respondent to the aforesaid cycles of abrupt terminations of current in said track, a receiving circuit comprising a source of electrical energy and means to control said source of energy to amplify the brief impulses produced in said receiver, a transformer in said receiving circuit, a polarized relay selectively responsive to the polarity of individual impulses produced in said receiver, a vehicle wheel, means to count the revolutions of said wheel, and a train control magnet controlled by said polarized relay and by said means to count.
18. In a train control system, a track, vehicles on said track, a track controller system to set up in said track currents in two directions and abruptly to terminate them in predetermined cycles, a receiver on one of said vehicles wherein cycles of brief impulses of two polarities are induced respondent to the aforesaid cycles of abrupt terminations of current in said track, a receiving circuit comprising a source of electrical energy and means to control said source of energy to amplify the brief impulses produced in said receiver, a transformer in said receiving circuit, a polarized relay selectively responsive to the polarity of individual impulses produced in said receiver, a vehicle wheel, a circuit breaker operated by said wheel, a series of relays controlled by said circuit breaker over alternate paths to register the revolutions of said wheel, a vehicle brake, a brake control means applying said brake after a predetermined number of revolutions of said wheel have been registered by said series of relays, and means controlled by the operation of said polarized relay to clear said series of relays of any registered revolutions at predetermined intervals whereby said brake control means is prevented from applying said brake if said polarized relay operates at intervals sufficiently brief relatively to the speed of revolution of said vehicle wheel.
19. In a train control system, a track, vehicles on said track, a track controller system to set up in said track currents in two directions and abruptly to terminate them in predetermined cycles, a receiver on one of said vehicles wherein cycles of brief impulses of two polarities are induced respondent to the aforesaid cycles of abrupt terminations of current in said track, a receiving circuit comprising a source of electrical energy and means to control said source of energy to amplify the brief impulses produced in said receiver, a transformer in said receiving circuit, a polarized relay selectively responsive to the polarity of individual impulses produced in said receiver, a vehicle wheel, means to count the revolutions of said wheel, a brake control means applying said brake after a predetermined number of revolutions of said wheel have been registered by said series of relays, and means controlled by the operation of said polarized relay to clear said series of relays of any registered revolutions at predetermined intervals whereby said brake control means is prevented from applying said brake if said polarized relay operates at intervals sufficiently brief relatively to the speed of revolution of said vehicle wheel.
20. In a train control system, a track, a moving vehicle, a track impulse timer producing positive and negative impulses in said track, a receiver on said vehicle comprising a polarized relay, an armature forming part of said polarized relay permanently left in one position following a positive impulse and permanently left in an alternate position by a negative impulse, and means to compare the time said armature is left in one position with the time taken by said vehicle to move a predetermined distance.
21. In a train control system, a track, a vehicle on said track, a source of electrical energy to furnish energy for impulses in said track, a code timer to determine a plurality of different codes of impulses of two polarities in said track, the codes differing by the time elapsing between impulses of opposite polarity and a receiver on said vehicle differentially responsive to the different codes.
22. In a train control system, a track, a vehicle on said track, a wheel of said vehicle rolling on said track, a travel-indicator comprising said wheel, a receiver on said vehicle comprising a relay having two positions and train control elements on said vehicle operatively dependent on the time between reverses of position of said relay and on the indications of said travel indicator.
23. In a train control system, time measuring means including a track impulse timer and a receiver, distance measuring means comprising a wheel, a circuit controller connected to said wheel and a series of energized relays successively deenergized by said controller, and hold over means briefly to delay deenergization of one of said relays.
24. In a train control system, a track, a vehicle, a circuit-controlling device on said vehicle, and a counter variably operable by a plurality of groups of impulses, said counter comprising at least one relay for each unit to be counted.
25. In a signaling system, a set of counting relays, means for producing two distinct signals, an energizing circuit for one of said relays closed in response to the production of one of said signals, energizing circuits closed for all said relays upon the energization of said one of said relays, means responsive to the production of the other signal for

opening one of said energizing circuits, a separate energizing circuit for each relay, and an interrupter for controlling said separate circuits.

26. In an impulse counting system, a set of counting relays, an energizing circuit for one of said relays, energizing circuits closed for all said relays upon the energization of said one of said relays, an interrupter, and a separate energizing circuit for each relay controlled by said interrupter.

27. In a counting relay circuit, a series of energized relays, each energized by a path through a front contact of a prior relay, a control circuit likewise energizing alternate relays of the series, a second control circuit energizing other alternate relays, an interrupter alternately opening the two control circuits and deenergizing the relays one at a time successively, and a restoring circuit to reenergize the first relay of the series.

28. In a signal control system, means for producing two distinct signals, a series of counting relays, an energizing circuit closed for one of said relays in response to the production of one of said signals, an energizing circuit for each of the other relays closed by a preceding relay, means for opening the energizing circuit of said one of said relays in response to the production of the other signal, an interrupter, and a locking circuit for each relay controlled by said interrupter.

29. In a train control system, a polarized relay, two contacts, an armature on said polarized relay alternately closing said contacts, a slow-acting relay controlled by each of said contacts, a vehicle, a wheel thereon, an interrupter driven by said wheel, and a set of relays jointly controlled by said slow-acting relays and by said interrupter.

30. In a train control system, a travel recording device, a timed means periodically to reset said recording device, a brake, a brake applying means operable by said recording device, a manually operable braking means, and means operable by said braking means to prevent operation of said brake applying means.

31. In a train control system, a vehicle, a vehicle wheel, a signal receiver, a revolution counter assuming a plurality of successive positions operated by said wheel and reset at intervals to the starting position by said signal receiver, an automatic braking device for said vehicle operated by said revolution counter when it is in advanced position, and a manual braking device on said vehicle resetting said revolution counter to a position between the starting position and the advanced position mentioned.

32. In a train control system, a track; vehicles on said track; distance measuring means on one of said vehicles comprising a wheel, two control circuits, an interrupter operated by said wheel alternately to open

said two control circuits, and a series of normally energized counting relays in two groups, each group being held energized by one of said control circuits, and each individual relay of the series except the first being additionally held energized by the energized position of an earlier relay of the series; time measuring means comprising means including said track to transmit to said vehicle timed electrical impulses of alternate polarity; receiver means responsive to the timed impulses; and energizing circuit for the first of said series of counting relays, and hold over means controlled by said time measuring means to maintain closed said energizing circuit during periods of relatively frequent timed impulses and to open said energizing circuit between relatively infrequent timed impulses.

33. In a continuous indication train control system, in combination, a magnet on the train, means controlled by traffic conditions for energizing and deenergizing said magnet at regular intervals, a circuit controller operated by said magnet, and a train control circuit through said circuit controller held closed so long as the interval between successive energizations of said magnet does not exceed a predetermined time.

34. In a continuous indication train control system, in combination, a magnet on the train, means controlled by traffic conditions for energizing and deenergizing said magnet at regular intervals, a circuit controller operated by said magnet, and a train control circuit through said circuit controller held closed only so long as the interval between successive energization of said magnet does not exceed or fall short of a predetermined time.

35. In a train control system, in combination, a track, a vehicle travelling thereon, a translating device on the vehicle, a timing device on the track, means controlled by said timing device for transmitting electrical impulses through said translating device, a timing device on the vehicle, and indication means under the joint control of said translating device and the timing device on the vehicle.

36. A railway signaling system, comprising a track divided into insulated blocks, means for applying to the rails of a block alternately and periodically two distinctly different electrical currents, and indication means for the blocks controlled by said currents.

37. A railway signaling system comprising a track divided into insulated blocks, means for applying to the rails of the blocks continuous current periodically alternating in polarity under clear conditions, means for intermittently applying to a block current of one polarity under caution conditions, means for intermittently applying to said

block current of the other polarity under danger conditions, and signals for the blocks selectively responsive to said currents.

38. A railway signaling system comprising a track divided into blocks, means operating under normal conditions to connect local sources of direct current across the rails of the blocks and to reverse periodically the connections of said sources to the rails, a vehicle having contacts engaging the rails, a polarized relay connected to said contacts having an armature vibrating in unison with the reversals of current in the rails, two slow-release magnets having circuits alternately closed by said armature, and a clear signal having a circuit including front contacts of said magnets.

39. Railway traffic controlling apparatus comprising means for supplying the track rails with energy in the form of spaced groups of impulses, a relay arranged to be energized when the rails are being supplied with said impulses but to be deenergized between groups, and traffic governing means controlled by said relay.

40. Railway traffic controlling apparatus comprising traffic governing mechanism on a railway vehicle, a selector on said vehicle for controlling said mechanism, and code impulse transmitting means located in the trackway for controlling said selector.

41. In an automatic train control system, means for communicating an impulse corresponding to traffic conditions from the trackway to a moving vehicle comprising trackway apparatus for recurrently impressing a predetermined series of time-spaced electrical impulses on trackway conducting means, car-carried means for inductively receiving said impulses, and car-carried apparatus operated synchronously with said trackway apparatus for responding to said impulses.

42. In an automatic train control system, means for communicating influences corresponding to traffic conditions from the trackway to a moving vehicle comprising trackway apparatus, apparatus for recurrently impressing one of a plurality of predetermined series of time-spaced impulses on the track rails, each of said series of impulses representing certain traffic conditions ahead, means for inductively transmitting said impulses to a moving vehicle, and car-carried means operated synchronously with said trackway means for responding to said impulses.

In witness whereof, I hereunto subscribe my name this third day of January, 1923.

ARTHUR H. ADAMS.
